UNITED STATES PATENT OFFICE.

GEORGE C. KNAUFF, OF CHICAGO, ILLINOIS.

METHOD OF FORMING PROJECTIONS.

1,142,820.

Specification of Letters Patent. Patented June 15, 1915.

Application filed August 17, 1912. Serial No. 715,607.

To all whom it may concern:

Be it known that I, GEORGE C. KNAUFF, a citizen of the United States, residing at Chicago, in the county of Cook and State 5 of Illinois, have invented a certain new and useful Improvement in Methods of Forming Projections, of which the following is a full, clear, concise, and exact description, reference being had to the accompanying 10 drawings, forming a part of this specification.

My invention relates to processes or methods for forming raised portions or projections upon the surface of materials, its 15 object being to obtain a secure and rigid fastening for the material of which each projecting part is made, without the use of cement or of any auxiliary retaining member; also to secure an exact and unchangeable 20 distance between the exposed tip of the projecting material and the surface from which this material projects.

My invention is particularly applicable to the construction of articles made in part of 25 hard rubber, as for instance, in forming the projections which serve as anchoring elements upon the rubber plugs, used with automobile lighting sockets. In securing such projection-forming pins to the rubber 30 bodies, it has heretofore been customary either to cement them in place, or to depend on a tight driving fit for holding them. Neither of these methods have proven satisfactory 35 with changes in the temperature and humidity of the air to which articles of this class are exposed. Moreover, it has been difficult with these methods to assemble the parts when the anchoring pin is to project only a slight distance beyond the 40 surface of the rubber plug, or to secure a uniform projection of the same.

My invention obviates these difficulties and is particularly adapted for forming 45 metal projections of a slight but definitely predetermined height upon a member of insulating material. It is shown in this application in the accompanying drawings, in which—

Figure 1 shows an elevation of an attachment 50 plug before the insertion of the metal member which is to form projections upon the plug at both ends, a part of the plug being cut away to show a section of the interior. Fig. 2 shows an elevation of the 55 metal projection-forming member before insertion. Fig. 3 shows a partial section of

the plug with this metal member united to it but not yet cut off at its ends. Fig. 4 shows an alternative form of metal member. Figs. 5 and 6 are sections along lines 5—5 60 and 6—6 in Fig. 4. Fig. 7 shows a partial section of a plug with perforations passing part way through the same for receiving projection-forming materials. Fig. 8 shows a metal projection formed upon a 65 rubber plate by my process. Fig. 9 shows the method of inserting the metal projection-forming member shown in Fig. 2 in the plug shown in Fig. 1. Fig. 10 shows the method of cutting off the surplus length 70 of the metal member required for inserting the same by the method shown in Fig. 9.

In the drawings, A is an attachment plug 75 of hard rubber, having a body B with a transverse perforation C.

D is a metal member having a section at both ends substantially equal to the bore of the perforation C.

E is a raised thread formed on the central portion of the member D. To insert this 80 member D in the perforation C, I soak the rubber body D for some time in water heated close to its boiling point (or to about 205 degrees Fahrenheit), thereby softening the surface portions of the rubber, including 85 the wall of the perforation. I then grasp one end F of the member D between the jaws of the chuck G of a drill press H as shown in Fig. 9 and rotate the chuck while the body B is kept from turning by resting 90 in a non-rotatable grooved support I. On raising this support while the member D is being rotated, the thread E compresses the softened portions of the rubber body B adjoining the perforation, thereby allowing 95 the member D to thread its way through the body B. Then, when the assembled parts B and D are allowed to cool, the compressed portions of the rubber endeavor to resume their original volume, thereby gripping the surface of the thread E so tightly 100 that I have found it impossible to move the member D with reference to the body B so as to alter the distance to which the ends of the former project.

The length of the threaded portion of the insertible member is preferably made somewhat less than the length of the perforation. Then when the said member is inserted until the perforated member completely houses 110 the threaded portion of the other member (as in Fig. 3) the portions of the perforated

member at each end of the perforation will contact with unthreaded portions of the inserted member. Consequently, when the perforated material hardens, it will form contracted portions around the inserted material at each end of the perforation, which portions will act as stops to prevent the unscrewing of the inserted member.

In carrying out my process, I preferably 10 give the member of which the projections are to be formed a cylindrical form, and roll raised threads upon the same. However, I have found that instead of rolling the thread upon this member, the central portion of the 15 insertible member may be stamped out as in Fig. 4, and provided at opposite edges with staggered teeth J, which will press back the rubber and thread their way into the softened walls of the perforations C, 20 thus serving the same purpose as the form shown in Fig. 2. I have also found that my process serves equally well with perforations extending only part way through the softenable body as shown in Fig. 5, in which 25 K is a perforation entering the body from one side and L is a metal member inserted into a corresponding opening on the other side of the plug M. Consequently, my method will serve equally well for making 30 the desired projections singly or in oppositely disposed pairs.

I have also found that the method of my invention will serve equally for forming raised metal projections upon sheets of insulating material, as shown in Fig. 8, in which N is a plate of hard rubber and O is a metal switch pivot inserted in the same by my process. In thus securing metal projection-forming members to sheets or plates, 35 it is not necessary to soak the whole plate in hot water, as the softening influence may be employed in the form of a jet of hot water or steam sprayed upon the portions of the plate or sheet adjacent to the perforation in which the metal member is to be inserted. Where a number of such metal projections are thus united with a single plate, as in the making contacts for a rheostat, the 40 whole group of projections may be trimmed 45 down to the desired height simultaneously by means of a grinding disk.

Where the projections are oppositely disposed as in the attachment plug shown in Patent No. 1026269 granted to me May 14, 50 1912, I preferably trim both of the projections simultaneously to the desired height by resting the rubber body in the socket portion of die P, as shown in Fig. 10, and cutting off the surplus length of the inserted projection-forming member D with a die R.

It will be obvious from the above that the extent to which the projection-forming material projects above the material into which it is anchored, can readily be determined 65 with accuracy and uniformity; that where

such projections are to be oppositely disposed, the distance between the tips of the opposite projections can be accurately predetermined; and that the projection-forming material will be so firmly anchored as not to permit of any change in the dimensions thus determined.

I am aware that such projections have heretofore been produced by driving or twisting a bar through an orifice into which it fits tightly. But I have found in practice that it is difficult to stop the inserted bar at the exact points corresponding to the desired projection of the bar, and that even when thus stopped, the bar will slide to and fro later on so as to vary the distance to which it projects. By starting with a surplus length of the inserted material, I avoid the need of great exactness in stopping it at the right point and make it an easy matter to obtain any desired amount of projection.

I am aware that threaded members have heretofore been anchored in wood or similar moisture-absorptive materials by softening the wood with a liquid, such as a solvent of glue, inserting the threaded member while the wood is thus softened and therefore yielding, and permitting the softened and glue-saturated wood to harden. However, such a process could only be used with materials like wood which will absorb moisture, and the resulting anchoring of the inserted member was dependent upon the action of the adhesive carried by the solvent. Consequently, this older process is not applicable 100 with amorphous and non-moisture-absorbive materials, such as hard rubber.

While I have illustrated and described my process as applied to the producing of metal projections upon hard rubber, and as using 105 steam or hot water as the softening influences, it will be evident that my process will be applicable also to other materials and that softening influences other than water or steam may be used in the process; also that 110 my process is particularly applicable to amorphous materials which are normally unyielding and incomprehensible. It will also be evident that the above described method of anchoring inserted parts in a softenable 115 material may be used for other purposes than the forming of projections, but I do not here claim it in such other connections, the latter being covered by my copending application filed March 11, 1912, Serial No. 120 683058, of which this application is a division.

I claim as new and desire to cover by Letters Patent:

1. The method of forming an immovable 125 projection of pre-determined height upon a member composed of an amorphous, normally unyielding and non-moisture-absorptive material without the use of an adhesive, which consists in perforating the member 130

- where the projection is to be formed; subjecting the member to a heating and softening influence until the wall of the perforation is sufficiently softened to render the same plastic; inserting into the perforation while the wall thereof is in the said plastic condition a member equipped with raised portions, thereby causing the said raised portions to compress the plastic wall of the perforation and to embed themselves in the said wall while being inserted; the said inserted member being of a material normally unyielding and unaffected by the said softening influence and having an excess of length by which it may be manipulated for insertion; allowing the softened and compressed portion of the perforated member to harden and anchor the inserted member by pressure upon the latter; and cutting off the exposed surplus length of the said inserted member.
2. The method of forming oppositely disposed immovable projections of predetermined heights upon a member composed of a normally unyielding material, which consists in perforating the member along the common axis upon which the desired projections are to be located; subjecting the member to a heating and softening influence until the wall of the perforation is sufficiently softened to render the same yielding; inserting into the perforation while its wall is in the said yielding state a member composed of a material which is normally unyielding and which is unaffected by the said softening influence, the said inserted member having raised portions adapted to compress the softened wall of the perforation while being inserted; the said inserted member being greater in length than the distance between the tips of the desired projections, the excess in length enabling it to be manipulated for insertion; allowing the softened and compressed wall of the perforation to harden; and cutting off the exposed surplus length of the inserted material.
3. The method of forming oppositely disposed immovable projections of predetermined heights upon a member composed of a normally unyielding material, which consists in perforating the member along the common axis upon which the desired projections are to be located; subjecting the member to a heating and softening influence until the wall of the perforation is sufficiently softened to render the same yielding; screwing into the perforation (while its wall is in the said yielding state) a member composed of a material unaffected by the said softening influence, the said latter member having upon a portion of its length raised threads adapted to compress the softened wall of the perforation while being inserted; the said inserted member being greater in length than the distance between the tips of the desired projections, the excess in length enabling it to be manipulated for insertion; allowing the softened and compressed wall of the perforation to harden; and cutting off the exposed surplus length of the inserted material.
